UNITED STATES PATENT OFFICE.

GEORGE HUTCHINSON, OF NAPIER, NEW ZEALAND, ASSIGNEE TO DONALD-HUTCHINSON PATENTS, LIMITED, OF MASTERTON, WELLINGTON, NEW ZEALAND.

FENCING-POST.

1,180,721.

Specification of Letters Patent. Patented Apr. 25, 1916.

Application filed July 18, 1913. Serial No. 779,739.

To all whom it may concern:

Be it known that I, GEORGE HUTCHINSON, a citizen of the Dominion of New Zealand, and residing at Napier, in the Provincial District of Hawkes Bay, in the Dominion of New Zealand, have invented certain new and useful Improvements in Fencing-Posts, of which the following is a specification.

The invention relates to metal posts for wire fencing and the like.

According to my invention a post is formed of sheet or plate metal cut to the required shape, and then bent to produce a post of V cross section tapering from what is the ground line in use, and provided with substantially parallel portions at the outer ends of the legs of the V.

The invention is illustrated in the drawing wherein:

20 Figure 1 is a plan of a metal blank. Fig. 2, a side perspective elevation of the post. Fig. 3, a part side sectional elevation on line A A Fig. 2 (illustrating the attachment of a fencing wire). Fig. 4 is a sectional plan of Fig. 2 taken on the ground line.

The metal blank, 1, Fig. 1, is formed to the shape shown tapering from the ground line (indicated by the dotted line 2) upon both edges 3 and 4 toward the top and upon both edges, 5 and 6, toward the bottom which forms the driving point, 7, of the post. By shaping the blank in this way the maximum sectional area, and consequent strength, is obtained at the ground line, 35 while the material is reduced toward the top where the strain likely to be brought to

bear upon the post when in use is relatively less.

The blank is bent (as shown in Figs. 2 and 3) into approximately V section with the approximately parallel side wings 8 and 9, which wings add greatly to the strength of the post.

The fencing wires may be secured across the apex of the V, or across the wings 8 and 9, and any usual connecting means may be employed. For the purpose of illustration a method is shown in Fig. 3 consisting of a staple 10, which is passed through a hole, 11, in the edge of wing 8, and has its ends, 12 and 13, bent around the wire 14.

If the post is to be driven into soft ground the lower end need not be tapered, but it is usually convenient to use the taper, as saving in weight is thereby effected.

What I do claim and desire to secure by Letters Patent of the United States is:

A fencing post consisting of a V-shaped strip of sheet metal tapered, from the portion representing the ground line, toward both ends, the extreme outer ends of the legs of the V being inwardly turned relatively to said legs to form flanges both above and below the portion representing the ground line.

In testimony whereof I have signed my name to this specification in the presence of two witnesses.

GEORGE HUTCHINSON.
